UNITED STATES PATENT OFFICE.

WILLIAM R. BIDDLE, OF CINCINNATI, OHIO.

TRANSFER-TICKET.

1,302,758.

Specification of Letters Patent.

Patented May 6, 1919.

Application filed May 15, 1916. Serial No. 97,489.

To all whom it may concern:

Be it known that I, WILLIAM R. BIDDLE, a citizen of the United States, and residing at Cincinnati, in the county of Hamilton and State of Ohio, have invented a new and useful Improvement in Transfer-Tickets, of which the following specification is a full disclosure.

My invention relates to an improved street car transfer ticket.

The object of the invention is to produce a transfer ticket which can be used for either local traffic, as in the city street car system, or interchangeably with another system or systems, such as a belt or express line, having points or stations of intersection with the city line, or other interurban lines.

Another object of the invention is to produce a very simple ticket on which the conductor can readily indicate the transfer usages and which the passenger will readily understand so as to assist the passenger and at the same time prevent abusage of the transfer privilege.

Another object of the ticket is that it enables the conductor when desirable to route the passenger by a punch system which also furnishes to the passenger a direction diagram, not only preventing misunderstanding, but affording practical assistance for making proper connections and for selecting the most direct route available.

The features of the invention will be more fully set forth in the description of the accompanying drawings, forming a part of this specification, in which:—

Figure 1 is a plan view of the transfer ticket. Fig. 2 shows portion of modified form.

The ticket comprises a non-coupon rectangular strip 1, the outer margin of which has the two vertical hour columns 2—2 with the minute sub-divisions 3, it being very convenient and more accurate to indicate the hour by punching the extreme lateral margins where there is more available space.

Within the medial portion of the ticket, defined by rectangular lines 4, is a tabulation of the city car lines 5, such as "Oakley" "Sedamsville", etc., and the various interurban lines, such as "Millcreek", "Glendale", "C. M. & L.", etc., and this tabulation is further divided by a vertical line 6, into an out-column 7 and an in-column 8, and preferably there is a meridian indication 9 to

be punched within the space defined by the rectangular lines 4.

Surrounding this city car line table on four sides is a belt or express line space 10 which is separated from the time table by a rectangular line 11 and from the city car lines by the rectangular line 4. Within this space 10 are arranged the belt or express line stations 12, as for instance, "Walnut Hills", "Madisonville", etc., and preferably the arrow indications 13 are placed on each side of the belt or express line stations. Also preferably the top belt or express line space is marked "South", the bottom "North", the right hand side "West" and the left hand space "East."

In purely city transfer usage, this space would not be utilized and the conductor would simply punch the desired city issuing line and transfer line. However, if the transfer is to be used from a city line to a belt or express line, the conductor would punch the city issuing line (say Sedamsville) and the nearest available station for taking the belt or express line, say "Foot of Eighth", by punching arrow showing direction for shortest route and the destination transfer point, say "Madisonville." Also if it is desired, the conductor indicates the route by approximately punching the arrow to one or the other side of Madisonville so as to diagram the direction of travel from Madisonville, as north or south, or at option of the company he could punch Madisonville and then the words "North" or "South", and so indicate the direction and the shortest route.

It is to be understood that the belt line is not the regular urban line, but an encompassing or encircling line, circuiting the outlying suburbs. In the example stated, punching one of the arrows adjacent the "Foot of Eighth street" indicates the transfer point of urban and belt lines intersection, and punching "Madisonville" indicates the destination point on the belt line. If the shortest routing from the urban line is toward the south, the upper arrow would be punched adjacent "Foot of Eighth street", or if north, the lower arrow would be punched. If the north is the best route, the passenger at the foot of Eighth street takes a belt line car on its northern trip. Madisonville is east of the foot of Eighth street, but as the belt line is a loop line, the

car going one direction will reach the east station through the northern zone, and the car in the other direction will reach this east point by way of the southern zone. If north 5 is indicated, the passenger takes the belt line going north at the foot of Eighth street, which later turns east toward Madisonville. He can only get to Madisonville on the belt line by taking a north or south bound belt

10 line car.

If the destination on the belt line from the transfer point is Carthage, the arrow pointing to the north is punched, as indicating the best routing.

15 The general directions of the belt loop marked "East" and "West" is north and south, and of the loop marked "North" and "South", the opposite general directions of the travel of these portions of the loop is 20 north and south.

Also, if it is desired for such interchangeable transfer, the city line issuing could punch the issuing city line as "Sedamsville", and then the appropriate belt or express line 25 destination, or transversely, the belt or express line could indicate the belt or express issuing point and the city destination point.

This ticket is susceptible of a variety of usages depending upon the varying conditions and rules, and the provision not only 30 prevents misuse, but enables a quick and accurate determination to be made in a very simple manner, which is easily understood by the passenger and with a minimum number 35 of punch holes required.

This transfer ticket is a material assistance to the traveling public, as well as restricting the permissible usage to prescribed regulations.

Preferably there is a medial space 16 to 40 be punched between the two tables of city lines, and this is designated "Issued by" which enables the issuing line to so indicate beyond possibility of mistake.

Having described my invention, I claim: 45

A routing transfer ticket for coördinating urban lines with a loop line, comprising a rectangular strip of paper having a time limit tabulation to be punched on the cutter margins, a medial portion of the strip containing tabulations of street car lines with appropriate out and in indications, a rectangular belt line space to be punched bordering the street car tabulation, and containing compass indications charting the general 50 directions of the loop, said belt line space also containing direction indications to be punched, and the names of places through which the belt line passes and intersects the urban lines, enabling directions and change 55 stations to be appropriately indicated by punching.

In witness whereof, I hereunto subscribe my name, as attested by the two subscribing witnesses.

WILLIAM R. BIDDLE.
